GEORGE HENRY ELWELL, OF BOSTON, MASSACHUSETTS, ASSIGNOR TO FRANK B.
HOPEWELL, TRUSTEE, OF NEWTON, MASSACHUSETTS.

HYPODERMIC CASE.

1,113,890.

Specification of Letters Patent. Patented Oct. 13, 1914.

Application filed November 3, 1913. Serial No. 798,979.

To all whom it may concern:

Be it known that I, GEORGE H. ELWELL, a citizen of the United States, and residing at Boston, county of Suffolk, State of Massachusetts, have invented an Improvement in Hypodermic Cases, of which the following description, in connection with the accompanying drawing, is a specification, like characters on the drawing representing like parts.

This invention relates to a pocket case for holding and carrying a hypodermic syringe and a set of vials containing various liquids for use in connection with the syringe.

The object of the invention is to provide a case of this type, compact in form, light in weight, simple in construction, cheaply manufactured, and of a character that may be readily sterilized without injury.

A further object of the invention is to provide a case of this type, which when in open position, will take a form enabling it to stand upright upon a table or other flat surface without additional support, thus holding the vials and syringe in such position that either or all may readily be removed therefrom, as required.

A further object of the invention is to provide a construction in which, when the case is in open position the compartments containing the vials will be laterally open, exposing the vials throughout their length, thus enabling the labels upon the vials designating the contents thereof, to be in full view preventing mistakes as to the contents, and enabling each to be readily identified.

A further object of the invention is to provide a case of this type in which the syringe itself locks the case in closed position by a simple engagement therewith of its usual transverse finger piece, and in which upon the removal of the syringe the case opens automatically, preferably by the use of a spring construction.

These and other objects of the invention will more fully appear from the accompanying description and drawings, and will be particularly pointed out in the appended claims.

Referring to the drawings in which I have illustrated a preferred form of my invention, Figure 1 is a side view of my improved case, the parts being shown in closed position. Fig. 2 is a longitudinal section,

the parts being shown in the same position; 55 Fig. 3 is a transverse section taken on the line 3—3 Fig. 2; Fig. 4 is a perspective view showing the parts of the case in open position, and Fig. 5 is a detail view of a portion of a wing member showing a wall member 60 detached from the ring before it is twisted into final position.

Referring to the drawings in detail I have illustrated a two part case consisting of a pair of centrally pivoted sections each section presenting oppositely extending wings. One section is shown as consisting of a central tubular member 1, a base plate 2, and oppositely extending wing members 3 and 4. The other section consists of a top plate 65 5 and oppositely extending wing members 6 and 7. This section is pivotally mounted on the tubular member 1 of the first section and is so connected thereto that a limited longitudinal movement is possible. The 70 base and top plates are circumferentially flanged as indicated at 8 and 9. The lower ends of the wing members 3 and 4 are positioned within the flange of the base plate 2 and soldered thereto, and the upper ends of 80 the wing members 6 and 7 are similarly secured to the top plate.

The free ends of the wing members are adapted to be received within the flanges of the opposed top plate and base plate when 85 the case is closed, thus interlocking the sections. The aforesaid longitudinal movement therefore serves to interlock and to release the sections. I provide for thus interlocking the parts in order to make the case more 90 rigid and substantially dust proof so that it may more safely be carried loose in the pocket.

Each wing member is corrugated in a manner to present recesses or pockets 10 in 95 one face. I prefer this corrugated shape as it is strong and conveniently manufactured and provides a simple method of forming the compartments. The two wing members of each section are so positioned that the recesses are presented on opposite sides of the section and the wing members of the two sections are reversely arranged so that the recesses are presented toward each other and thus coöperate to provide vial compartments. 100 Each wing member is provided at its inner edge with a ring 11 embracing the tubular member. The rings of the members 3 and 4 105

are preferably soldered to the tubular member, but the rings of the members 6 and 7 are freely rotatable thereon.

The recesses or pockets of wing members 3 and 4 are provided with retaining springs 12 to retain vials or the like in position. The central tubular member besides acting as the pivot member of the case presents a cellular compartment adapted to receive the 10 barrel of a hypodermic syringe 13. This tubular member extends above the rest of the case and is provided with L-shaped slots 14, with which the finger piece 15 of the syringe co-operates to form a bayonet joint 15 holding the syringe in position. The inner ends of the slots may be formed to provide retaining notches 16 to prevent accidental rotation of the syringe. The bayonet slots 14 are so positioned that the finger piece 15, 20 when in position in the inner ends of the slots, may lie longitudinally of and in contact with the top plate of the pivoted section to hold the sections in closed and interlocked position. A spring 17 is mounted in 25 the tubular member and acts to automatically open the case.

One end of the spring is secured in the base plate as indicated at 18 and the other end extends through an L-shaped slot 19 in 30 the side of the tubular member and is secured to the pivoted member as indicated at 20. The slot 19, co-operating with the spring determines the path of movement of the pivoted section. The longitudinal portion 35 of the slot permits longitudinal movement of this section to interlock and release the parts and the transverse portion permits swinging movement to open and close the case. The spring 17 is tensioned in two 40 directions so that it tends to move the pivoted section longitudinally and rotatably to open position.

The four wing members are shown as of similar shape and when so made may all be 45 stamped from sheet metal by using a single set of dies. The rings 11 may conveniently be formed integral with the wing members by stamping them out in the plane of the members, as shown in Fig. 5, and 50 afterward twisting them through an angle of 90°. In order that the edge of the wing members may lie close to the tubular member and form a tight joint, the rings are set back into recesses as indicated at 21 in Fig. 55. When twisting the rings one ring of each section is moved slightly upwardly and the other similarly downwardly so that the wing members will properly mate.

I have illustrated and described one practical embodiment of my invention. The invention, however, is not limited to the construction shown as it will be obvious to one skilled in the art that various modifications may be made without departing from the 65 spirit of the invention.

Having fully described my invention, what I claim as new and desire to secure by Letters Patent is:

1. A case of the character described comprising a pair of pivoted sections presenting wings extending at either side of the pivotal axis, two of said wings being recessed in parallelism to the pivotal axis to form vial pockets, the other two of said wings forming closures for the said pockets, whereby when the sections are swung into parallelism the case is closed and when swung at right angles the case may support itself in upright position with the several vials exposed and accessible. 70

2. A case of the character described comprising a pair of pivoted sections presenting wings extending at either side of the pivotal axis, two of the said wings being recessed in parallelism with the pivotal axis to form vial pockets, means in each of said pockets for retaining a vial therein, the other two of said wings forming closures for the said pockets, whereby when the sections are swung into parallelism the case is closed, 85 and when swung at right angles the case may support itself in upright position with the several vials exposed and accessible. 90

3. A case of the character described comprising a pair of sections, one presenting a central tubular member and the other pivoted on said tubular member, and both presenting wings extending at either side of the pivotal axis, two of the said wings being recessed in parallelism with the pivotal axis to form laterally open vial pockets, resilient means for retaining vials in said pockets, the other two of said wings forming closures for the said pockets, whereby when the sections are swung into parallelism the case is closed and when swung at right angles the case may support itself in upright position with the several vials exposed and accessible. 95

4. A case of the character described comprising a pair of interlocking sections, one presenting a central tubular member forming a cellular compartment adapted to receive the barrel of a hypodermic syringe provided with a transverse finger piece, and the other pivoted on said tubular member and slidably relatively and longitudinally thereof, both presenting wings extending at either side of the pivotal axis, two of said wings being recessed in parallelism with the pivotal axis to form laterally open vial pockets, resilient means for retaining vials therein, the other two of said wings forming closures for the said pockets, a spring secured at one end in said tubular member, its other end extending through a guiding slot in the side of the tubular member and secured to the pivoted section, thereby determining the path of opening and closing movement of the pivoted section, said spring being ten- 100 110 115 120 125 130

- sioned normally to hold the sections in open position, means for holding the hypodermic syringe in position in the central cellular compartment in such a manner that the 5 finger piece of the syringe will hold the pivoted section in closed position, whereby when the sections are swung into parallelism and the hypodermic syringe is in position the case will be closed, and when the hypodermic syringe is removed the spring will 10 operate to move the sections to open position, whereby the case will support itself in upright position with the several vials exposed and accessible.
- 15 5. A case of the character described comprising a pair of interlocking sections, one presenting a central tubular member forming a cellular compartment adapted to receive the barrel of a hypodermic syringe 20 provided with a transverse finger piece, and the other pivoted on said tubular member and slidable relatively and longitudinally thereof, both presenting wings extending at either side of the pivotal axis, two of said 25 wings being recessed in parallelism with the pivotal axis to form laterally open vial pockets, resilient means for retaining vials therein, the other two of said wings forming closures for said pockets, a spring secured at one end in said tubular member, its other end extending through a guiding slot in the side of the tubular member and secured to the pivoted section, thereby determining the path of opening and closing 30 35 movement of the pivoted section, said spring being tensioned normally to hold the sections in open position, the tubular member having L-shaped slots near its upper end with which the finger piece of the hypodermic syringe may coöperate to form a 40 bayonet joint, and so positioned that the projecting ends of the finger piece may engage the movable section to hold it in closed position.
- 45 6. A case of the character described comprising a pair of pivoted sections presenting similar wings extending at opposite sides of the pivotal axis, each of said wings consisting of a shell corrugated to present recesses 50 extending in parallelism with the pivotal axis, the wings of one section being reversely arranged, whereby when the sections are

swung into parallelism the recesses will co-operate to form closed vial compartments, and when swung at right angles the case 55 may support itself in upright position with the several compartments laterally open throughout.

7. A case of the character described comprising a pair of interlocking sections, one 60 consisting of a central tubular member, a pair of wing members extending laterally from said tubular member and recessed in parallelism thereto to present vial pockets and a flanged base plate, said tubular member, wing members and base plate being 65 rigidly secured together the other section consisting of a pair of wing members extending laterally from said tubular member and a flanged top plate, said wing members 70 and top plate being rigidly connected together and rotatably and slidably mounted on said tubular member, whereby when the sections are swung into parallelism the case is closed, and when swung at right angles 75 the case may support itself in upright position with the several vials exposed and accessible.

8. A case of the character described comprising a pair of interlocking sections, one 80 presenting a central tubular member and the other pivoted on said tubular member and slidable relative thereto, and both presenting wings extending at opposite sides of the pivotal axis, two of said wings being recessed in parallelism with the pivotal axis to form laterally open vial pockets, means for retaining vials therein, the other two of said 85 wings forming closures for the said pockets, one end of one section being shaped to receive the ends of the wings of the other section, whereby when the sections are swung into parallelism and moved longitudinally the case is closed and the sections thereof 90 interlocked and when swung at right angles 95 the case is open and the several vials accessible.

In testimony whereof, I have signed my name to this specification, in the presence of two subscribing witnesses.

GEORGE HENRY ELWELL.
